H. DIGRE & J. NELSON.
BELT GUIDE AND THROWER.
APPLICATION FILED JUNE 9, 1915.

1,173,935.

Patented Feb. 29, 1916.

UNITED STATES PATENT OFFICE.

HENRY DIGRE AND JOSEPH NELSON, OF TORONTO, SOUTH DAKOTA; SAID NELSON
ASSIGNOR TO ELMER E. EVESON, OF TORONTO, SOUTH DAKOTA.

BELT GUIDE AND THROWER.

1,173,935.

Specification of Letters Patent. Patented Feb. 29, 1916.

Application filed June 9, 1915. Serial No. 33,141.

To all whom it may concern:

Be it known that we, HENRY DIGRE and JOSEPH NELSON, citizens of the United States, residing at Toronto, in the county of 5 Deuel, State of South Dakota, have invented certain new and useful Improvements in Belt Guides and Throwers; and we do hereby declare the following to be a full, clear, and exact description of the invention, such 10 as will enable others skilled in the art to which it appertains to make and use the same.

This invention relates to improvements in means for guiding and shifting a belt with 15 relation to a pulley, and is more particularly directed to the provision of such a device adapted to be associated with the drive belt of a threshing machine end or like structure having a pulley at the end 20 of a shaft whereby upon actuation of the device, the belt will be forced off the pulley and entirely detached from the engine structure.

It is the object of the invention to provide 25 such a device which may be readily and efficiently operated and which has its parts so arranged as to form a compact and relatively simple structure, which will prove durable in use.

With the above and other objects and advantages in view, the invention resides more particularly in the novel combination, formation and arrangement of parts as more 30 fully hereinafter described and pointed out 35 in the appended claims.

Reference is had to the accompanying drawing, wherein similar characters of reference designate corresponding parts throughout the several views, and in which:

Figure 1 is a side elevation of the improved device, showing the same in position to hold a belt in place on a pulley. Fig. 2 is a similar view of the device, but showing its parts extended to throw the belt 45 off the pulley. Fig. 3 is a central vertical longitudinal sectional view through the device. Fig. 4 is a bottom plan view. Fig. 5 is a transverse sectional view taken on the line 5-5 of Fig. 4, showing the operating 50 means for the drive shaft of the device. Fig. 6 is a detail sectional view on the line 6-6 of Fig. 5.

Referring particularly to the accompanying drawing, 5 designates the body portion

of the device which comprises a plate member having one end portion provided with lugs 6 whereby it may be readily attached to an engine structure in such manner that the body extends between a belt when in position on a pulley, a belt being designated 55 at 7 in Fig. 1. A slide member is provided comprising a relatively long portion 8 and a shorter outer portion 8' connected thereto by a hinge 9 having its leaves countersunk in the bottom faces of the portions whereby 60 the shorter portion may swing downwardly, this slide member being slidably held on the face of the body by flanges 10 having their inner faces beveled to slidably engage bevel 65 sides of the said sections, the section 8 carries 70 an upstanding roller 11 and the section 8' carries a similar roller 12, these rollers being secured rotatably on the section by the pins 13 passed therethrough and being adapted when the slide member is in the retracted position, shown in Fig. 1, to form 75 a guide means for holding the belt on the pulley. The outer end of the body portion is beveled at 14 and the slide member is adapted to be slid outwardly on the body 80 so that the roller 11 engages the belt and forces it laterally off the pulley, the outer section during this movement extending outwardly of the body so that it will drop and permit the belt to completely detach itself. 85 As the sliding member is retracted, the bevel portion 14 of the body engages the section 8' and raises it.

For moving the slide member, the bottom face thereof has formed thereon a longitudinal rib 15 toothed at 16 on its bottom face and slidable in a longitudinal groove 17 in the top face of the body, and a transverse shaft 18 is rotatably mounted on the bottom of the body through the medium of 90 suitable bearings 19 and carries a pinion 20 which engages through an opening 21 in the body to mesh with the teeth of the rib or rack member. This shaft may extend to any position desired to efficiently operate the 100 mechanism and may include a universal joint portion 22.

The operative end of the shaft 18 is journalled 105 held between vertical arms 23 carried by a bracket 24 suitably-supported on an engine and carries a suitable operating wheel 25. Pivoted between the free end of the arms 23 is a bar 26 which holds the shaft in the

arms and which is laterally extended past its pivot as at 27 to form a cam head whereby upon rocking the bar the shaft will be frictionally bound and thus held against 5 undesired movement to move the slide member.

This device is adapted to be attached on engine structures of various types, and to provide a brace means associated with the 10 body of the device which is adjustable for securement to any desired type of engine, a pair of spaced cleats 28 are secured longitudinally of the bottom of the body 5 and are provided with series of openings 29 15 which selectively receive a bolt 30 pivotally securing one end of a brace bar 31. The outer end of the brace bar is bifurcated at 32 to pivotally secure a shoe member 33 which is adapted to be bolted to the engine 20 structure as shown. Thus the brace is permitted a full degree of adjustment.

While we have illustrated and described a particular embodiment of our invention we have merely done so for the sake of convenience and we do not wish to be limited to that particular embodiment as it is obvious that numerous changes may be made 25 within the details of construction thereof without in any way departing from the spirit of the invention or exceeding the 30 scope of the appended claims.

Copies of this patent may be obtained for five cents each, by addressing the "Commissioner of Patents, Washington, D. C."

What we claim is:—

1. A device of the class described comprising a body member provided with a longitudinal dove-tail groove, a slide member held in the groove and comprising a relatively long section and a short section hinged thereto; guide rollers carried by each of the sections, the body being provided with an opening in its bottom communicating with the slot, a shaft journaled across said opening, a gear on the said shaft extending through the opening, and gear teeth formed on the bottom of the longer slide section. 45

2. A device of the class described comprising a body member, means for securing one end of the body member to a support and adjustable brace means for the intermediate portions of the body member including a longitudinal cleat thereon, a brace bar secured to the cleat and longitudinally adjustable with relation thereto, a shoe pivoted to the brace bar and means for securing said shoe to a support. 50

In testimony whereof, we affix our signatures, in the presence of two witnesses.

HENRY DIGRE.
JOSEPH NELSON.
